LUGGAGE HANDLE

Joseph Finkelstein, Glenside, Pa., assignor to Philadelphia Handle Company, Camden, N.J., a corporation of New Jersey

Filed Dec. 7, 1962, Ser. No. 72,766

Term of patent 14 years

(Cl. D87—2)

I claim:

The ornamental design for a luggage handle, substantially as shown.
